UNITED STATES PATENT OFFICE.

LE ROY FISH, OF NEW BERLIN, NEW YORK, ASSIGNOR TO BORDEN'S CONDENSED MILK COMPANY, OF NEW YORK, N. Y., A CORPORATION OF NEW JERSEY.

CAP-PLACING MACHINE.

1,188,638.

Specification of Letters Patent. Patented June 27, 1916.

Application filed December 18, 1914. Serial No. 877,946.

To all whom it may concern:

Be it known that I, LE ROY FISH, a citizen of the United States, and a resident of New Berlin, in the county of Chenango and State 5 of New York, have invented a new and useful Cap-Placing Machine, of which the following is a specification.

My invention, in its more general aspects, relates to the placing of caps on, and in, cans 10 preparatory to their being crimped, or otherwise secured thereto, to produce air-tight seams; and it relates particularly to thus automatically placing such relatively minute caps as are usually employed in the sealing 15 of such usually small, cylindrical, metallic, cans as are, in great quantities, used as containers for hermetically sealed merchandise, for example, condensed milk. Hitherto, I believe, such placing, including its indispensable 20 preliminary sorting and delivery of the caps, has been manual. For example, U. S. Letters Patent No. 1,029,326 to Burt Eugene Taylor, dated June 11, 1912, disclose automatic means to force such caps into, but 25 only "an operator" to "manually place" them on, the cans. The caps in question are, for the most part, small, attenuated, metallic, circular, rough-edged, disks, say about one 30 inch in diameter. They are usually had in lots, or quantities, comprising multitudinous intermixed, and more or less "nested", similar members. To quickly and effectively 35 separate these, one by one, from their aggregation, and transfer the isolated member to, and place it within the thereto closely fitting opening in the top of one of the filled cans awaiting its reception, not only requires exceptional adroitness, care, and skill, but also a delicacy of touch unattainable unless 40 the operator's fingers are so bare and unprotected as to be too often undesirably injured by friction from the rough edges, and with the consequent risk of germ-infecting the goods. A machine capable of dispensing 45 with all handling of the caps by the operator has therefore long been a desideratum.

The object of my invention comprises provision of means whereby, without contact by the operator, a single cap is, as often as required, sorted, in proper position, from its associates, transferred to the can-opening, placed thereon, and thereinto forced as required for subsequent sealing.

In a herewith contemporaneously filed application for patent Serial Number 877,947

I have disclosed means for so sorting, and, to an extent, separating the cap from its fellows, and also delivering it to a location whence it can be, mechanically, taken to be so placed. Taking the cap from this point 60 of delivery my herein claimed invention attains my said objects by means of the novel elements, and combinations of elements, illustrated in the accompanying drawings, in which:—

Figure 1 is a side elevation of important elements of my machine and means for operating the same; the endless chain belt being indicated, diagrammatically and in part, by a vertical section thereof; Fig. 2 is, on 70 reduced scale, a diagrammatic plan, partly in section on the line 2—2 of Fig. 1, indicating particularly some of the means assistant in the moving of the cans, and in the supporting them stationary; Fig. 3 is, on 75 enlarged scale, a central vertical sectional view of my cap-holder and plunger, and showing also some of the other therewith associated elements; Fig. 4 is a plan, partly in section, of Fig. 3 taken on the line 4—4 of 80 the latter; Fig. 5 is a detail, perspective view of one of the movable segments of my cap-holder; Figs. 6, 7, and 8 are diagrammatic elevations, partly in central vertical section, 85 illustrative of successive phases in the movements of the plunger, and some of its accessories, relatively to the cap and the can; Fig. 9 is a top-plan view of the movable segmental parts of my cap holder in their retracted, or open, position; Fig. 10 is, on a 90 still more enlarged scale, a top view of my inclined cap chute containing caps with parts broken away to show my movable stops and certain of their accessories for supporting the caps and for separating and 95 releasing one of them at a time; Fig. 11 is a view similar to Fig. 10, and showing a different stage in the operation of some of the parts thereby illustrated; Fig. 12 is a bottom view of Figs. 10 and 11 showing my 100 cam-plate containing angularly disposed openings for moving the stops; Fig. 13 is a side elevation of the chute, stops, and accessories shown in Figs. 10, 11 and 12; Fig. 14 is a section on the line 14—14 of Fig. 10; 105 Fig. 15 is a diagrammatic plan illustrating the positions of a can in which a cap has been placed, and of an as yet uncapped can, during their forward movement relatively to the trip-lever whereby a can controls the op- 110

eration of the cap-separating and releasing, and of the therewith coöperating cap-placing, instrumentalities; Fig. 16 is a similar view of the, as yet, uncapped can at the moment when it has fully actuated the trip lever whereby it controls the action of the said instrumentalities and has arrived at its position of stationary support. Fig. 17 is a central, vertical, section of part of a can and of a cap as therein placed by my instrumentalities. Fig. 18 is a view of the parts illustrated at Fig. 17 after the flange of the cap has been crimped to form the joint between the parts.

15. The metallic cans 19, shown in the drawings, are of uniform dimensions, and of the usual cylindrical type, having, in the top, a circular concentric opening 19', surrounded by the usual upwardly extending vertical flange 19² (Figs. 1 and 18). The metallic caps, indicated as an entirety by 20, are likewise of the usual circular type, consisting principally of a circular plane, disk-like, body, or portion, 20', having a 25 therefrom upwardly-extending annular neck 20² (dimensioned to closely fit the opening 19 in the can), and surrounded by a therefrom horizontally-outwardly-flaring flange 20³ (Figs. 17 and 18), the caps thus 30 embodying a bowl or recess 20⁴.

The final function of my herein claimed instrumentalities is to force the cap, previously thereby properly manipulated and placed, into the opening of the can in the 35 position indicated by Fig. 17 thereby fitting the parts to be crimped, or otherwise hermetically secured, together by any well known means, as for example by such a type of well known rotary crimper as is 40 shown and described in the above referred to Letters Patent No. 1,029,326 to Burt Eugene Taylor; which changes the relation of the parts to each other as indicated in Fig. 18.

45. For the operation of my novel devices I provide means to move, or feed, the filled, uncapped, cans, in procession, thereto, also to support them stationary in operative relation thereto, and to move them away 50 therefrom. Such means may be of any of those now known for the purpose, but I prefer those described and shown in said patent to Taylor, and have accordingly, to an extent diagrammatically, represented 55 them in my drawings, in which A (Figs. 2, 15, 16, etc.) indicates a horizontally movable endless sprocket chain, or endless-can-conveyer, carrying a plurality of therefrom horizontally-outwardly-projecting equidistant flights, or fingers, A', the interspaces A², between which are, as shown, equal to the diameters of the cans. A is also indicated, partly in vertical section, in Fig. 1. Intermittent movements of the endless conveyer are imparted thereto, and controlled

by, any convenient means;—as, for example, the sprocket wheels A³, A⁴, the latter an idler, and the former intermittently driven by aid of vertical shaft A⁵ (Figs. 1 and 2) carrying a disk A⁶, provided with pins A⁷, disposed to engage with pins A⁸, carried by a disk A⁹, carried by a constantly rotating horizontal shaft A¹⁰. The pins on the respective disks are, relatively to each other and to the other parts, so numbered, 70 spaced, and disposed as to cause the endless conveyer to advance, intermittently in the direction of the arrow a (Fig. 2) a distance equal to that between the centers of two adjoining spaces A².

B is a stationary table, or horizontal support for the cans, disposed partly adjacent to, and under, the fingers A which move them thereover. The cans, after having been filled, as, for example, with condensed milk, 80 by any well known means, are moved toward the endless conveyer, and into the interspace between two of the fingers A', in any convenient manner, as, for example, by aid of a can-carrying endless belt B', such as shown

in said Patent No. 1,029,326, on which they ride flush with the table B, and which is intermittently advanced by means timed to feed a can between the fingers of the endless conveyer during a pause in the advance 90 of the latter. The cans are fed to the belt B' in any desired manner. A procession of filled cans each disposed between a pair of fingers A', is, by the foregoing means, supported and moyed intermittently over the 95 table a distance equal to that between the centers of any two of the interspaces A² between the fingers A'.

The cans are, as usual, wherever required, guarded against undue transverse movements by any desired form 100 of stationary lateral guide rails A¹², A¹³, between which, the surface of the table B, and the chain A, is thus provided a pathway therefor. The instrumentalities operating

upon the caps, relatively to the cans, are 105 located so as to center with the latter during pauses in the advance of the endless can-conveyer. Thus, for example, the crimping devices employed may be, as in said Patent No. 1,029,326, located concentric with a station, in the can-pathway, indicated by B² in Fig. 2. Similarly my cap-placing devices are located so as to deliver, 110 place, and force a cap relatively to a can, concentrically with a station B³ (Fig. 2) 115 located, in the pathway, in advance of the crimper, thus providing the latter with a can and cap ready prepared for its operation, which occurs while another cap is, during the same pause in advance of the can-conveyer, being placed in another can. At 120 this last mentioned point, as indicated in Fig. 2, each can is temporarily supported, stationary, by coaction of the table B, the lateral guide-rails A¹² and A¹³, and, during 125

130

a pause in the advance of the conveyer A, by the two fingers A' which at that time contact opposite sides of the can.

I provide means to separate from its therewith contacting fellows a cap, to deliver it thus separated to a location above the so held stationary can, to adjust it there to proper and concentric position relatively to, and to force it into, the opening of the latter, all of which means are brought into play, *i. e.* controlled by the can itself as advanced to its stationary position by the endless can-conveyer.

My novel means, herein claimed, comprise the following devices, and combinations of devices, it being understood that formal, or equivalently functioning, variations therefrom are included in my invention.

Disposed above, and in concentric alignment with, a can when temporarily supported as aforesaid at the station B³, I provide a vertically movable plunger 21, having a therewith concentric, removable, presser-foot 21^a insertible in the recess 20⁴ of the caps 20. The presser-foot comprises, as shown in Fig. 3, a threaded shank 21^d screwable into the plunger, thus providing for interchangeability of differently dimensioned presser-feet to meet requirements of differently diametered caps. The plunger is slidably supported in a bearing C' carried by the stationary frame C of the machine, and is vertically reciprocated by aid of a lever-arm 22 (Fig. 1) one end of which contains a usual slot (not shown) through which loosely passes a pin 22^a carried by the plunger. The opposite end of the lever arm 22 is oscillatably joined with the frame C by a pivotal connection 22^b. The lever-arm 40 carries a pin 22^c and is intermittently oscillated as hereinafter described by a link 23, in this instance horizontally-oscillatably joined by the pivotal connection 24^a with a vertically-reciprocatable rod 24 slidably supported in the bearings C², C³, carried by the frame C. The rod 24 carries, adjacent its lower end, an arm 24^b provided with a pin 24^c normally bearing upon one of a plurality of concentric portions, 25^a, of a cam-disk, 25, carried by the shaft A¹⁰, and having a like plurality of intervening recesses, 25^b. The link 23 is constantly pulled downwardly by a retractable spring 26 connecting it with a stationary part, in this instance one of the bearings C³. Therefore as the disk 25 is rotated the pin 24^c is alternately raised and lowered and consequently also the link 23 can be vertically reciprocated.

60 The lever arm 22 is operatively connected with the link 23 by means of an opening, 23^a, in the latter, within which is loosely held the pin 22^c of the former. This opening has, as shown in Fig. 1, a transverse, or 65 horizontal, extension, and, at right angles

to the latter, a vertical extension in parallelism with the link. It follows that when the pin 22^c is in the horizontal portion of said opening the lever arm 22 will be vertically oscillated by the vertical reciprocations of the link, and the plunger 21 and its connections correspondingly reciprocated, but that the said reciprocations will not occur when the pin 22^c is in the vertical extension of the opening 23^a. The link 23 is also provided with a normally vertically-extending opening, or slot, 23^b, for a purpose soon to be described. By aid of this construction a can advancing through the pathway of the machine is enabled to control the movements of the plunger by the following means, viz.—A trip-lever 27 oscillatably-carried on a part of the frame C by the pivotal connection C²⁷, comprises a downwardly extending arm 27^a and an upwardly extending arm 27^b. 27^a carries a pair of alike antifriction rollers 27^c and 27^d (Figs. 1, 15 and 16) normally disposed to project into the pathway of the machine in the way of a therein advancing can. These rollers are, preferably, somewhat spaced-apart as shown, and the medial line between them, at right angles to the pathway, is coincident (Fig. 16) with that of one of the spaces A² during a pause in the advance of the endless can-carrier. The upwardly extending arm 27^b of the trip-lever 27 has an elongated slot 27^e. The trip-lever is adjustably connected with one end of a link 28 by a thereby carried bolt 28^a passing through said slot and provided with a lock nut 28^b to bind the parts as required to regulate the throw. The opposite end of the link 28 is pivotally secured to the upper end of a lever 29 oscillatably carried by the frame C, and comprising an upper arm 29^a and a lower arm 29^b. The lower arm 29^b is pivotally connected, as indicated by dotted lines in Fig. 1, with one end of a link 30, the opposite end of which is, as similarly indicated, similarly connected with an oscillatable arm 31 rotatably supported on a pivot C³¹ carried by the frame C as also indicated by dotted lines in Fig. 1. The arm 31 carries a pin 31^a extending through an arc-shaped opening C^a in the frame C, and also through the hereinbefore referred to vertical slot 23^b of the link 23 thereby engaging the latter.

It follows, from the foregoing construction, that a can advanced, as aforesaid, through the pathway of the machine, will trip the lever 27 thereby moving the horizontal extension of the slot 23^a to engage the pin 22^c in the position illustrated by Fig. 1, and thus providing for the down-forcing of the plunger 21. Also that the next intermittent advance of the can by the can conveyer will remove its outward pressure on the trip-lever, whereupon the latter and its

aforesaid connections are restored to normal position by the action of an expansile spiral spring 32 through which the link 28 is threaded and one end of which bears 5 against a stop 32^a carried by said link, and the other end against a bracket 32^b carried by the frame C, all as indicated by dotted lines in Fig. 1. The pin 22^c is thus restored to normal position, in alinement with the 10 vertical extension 23^a of the opening in the link 23, whereupon a compressible, or cushioning, spring, 33, interposed to bear against the lever arm 22 and a bracket 33^a carried by the frame C, will restore the lever 15 and thus the plunger 21 to normal position.

It will, of course, be understood that the relative proportions and dispositions of the elements referred to are such as to time the 20 descent of the plunger only during the pause of the can centered as aforesaid thereunder at the station B^a. Before the plunger can operate usefully, it is, however, essential that a cap be separated from its fellows, conveyed therefrom thus isolated, and placed, and supported, in proper position, 25 relatively to the plunger and the opening in the can. My present invention includes provision of means for these purposes as follows. By the aid of the invention claimed in my aforesaid herewith contemporaneous application for Letters Patent, the caps are brought, out of their confused and disorderly aggregation, into the comparatively orderly, but still undesirably contacting, and mutually-supporting, procession, in which they are shown in Fig. 10, to wit, bearing against each other in an inclined chute, 34, having a pathway there- 30 for leading from the sorting, positioning, and feeding, devices disclosed in my said application. To further detach, release, and 35 advance a cap from this mutually contacting and supporting procession, I provide, in the chute, a plurality of vertically disposed stops, or pins, in this instance two,—35 and 36 (Figs. 12—13) independently movable, as required, into, and out of, the pathway.

The chute 34 is adjustably, stationarily, 50 supported by any convenient means, in this instance, as shown in Fig. 1, by the thereto secured bracket 34^a having a slot 34^b through which passes a threaded pin C^b, carried by the frame C, the parts being 55 clamped together at the desired inclination by a lock-nut C^a. The chute comprises a floor 34^c (Figs. 13 and 14) inclined as shown in Fig. 1, also lateral guide-members, 34^d, having cap-overlapping extensions 34^e (Figs. 60 10 and 14). The floor of the chute is provided with a downward extension 34^f leading to a point of delivery beneath the presser-foot 21^a, and also, each side its medial line, with transverse openings, or slots, 34^g, 65 34^h, through which the pins 35, 36, respec-

tively extend and are movable in and out of the pathway. The pin 35 is carried by an oscillatable arm 35^a and the pin 36, similarly, by a like arm 36^a, respectively oscillatably-held to the under-part of the floor of the chute by pivots 35^b and 36^c. Underneath, and reciprocatable relatively to, the bottom of the chute, I provide a cam-plate 37 thereto slidably secured by headed screws 38 extending through longitudinal slots 38^a in said plate. The plate is also provided with angularly-extending openings, or cam-slots, 37^a, 37^b, through which respectively extend the pins 35 and 36. The normal position of the pins is as shown in Fig. 10 in which the pin 35 is stationary in the pathway of the procession of caps, the lowest member of which bears by gravity against the pin and thus assists in the support and retention all its followers in the chute. At 25 this stage the pin 36 is outside the pathway. The aforesaid construction is such that when the cam-plate in its reciprocations slides upward, i. e. toward the left in Figs. 10 and 11, the pin 36 is moved into the pathway to bear against the lower edge of the second cap in the procession which, with its followers, it forces slightly upward in the chute, thus separating the first cap from contact with the procession and holding back the latter, after which continued upward movement of the cam-plate moves the pin 35 out of the pathway, thus releasing the first cap which is then immediately conveyed by gravity down the inclined floor of 100 the chute, and its extension, to the place of its delivery, under the presser-foot 21^a. It will be noted that the first cap is thus effectively detached, and isolated, from the second, even though, as sometimes happens, 105 the flanges 20^a of the two are undesirably mutually overlapped as indicated in Fig. 10.

I provide means to reciprocate the cam-plate at the proper time as follows:—One end of a link 39 is secured to the cam-plate 110 by a pivotal connection 39^a (Fig. 1) the opposite end being likewise secured to the shorter arm (shown in dotted lines) of a lever 40 oscillatably-carried by a stationary pin 40^a carried by a bracket 34^m carried by 115 the chute 34. The long arm of the lever 40 is secured, by a pivotal connection 40^b, to the lower arm 29^b of the above described lever 29. The proportions, positions, and 120 relations, of these elements to each other, and to some of those hereinbefore described, are such that the cam-plate 37 is intermittently caused to slide upwardly, and a cap thereby separated and released, by the 125 advance of a can to its aforesaid station concentric with the plunger 21 and in advance of the descent of the latter.

The mere delivery by gravity, and as aforesaid, of a cap to a place under the presser-foot 21^a cannot, however, be relied 130

on to secure its proper placing, or insertion, by the latter, into the opening of the can; my invention therefore comprising also the following means to insure requisite accuracy of presentation, and support, of the cap so delivered, and during action thereon by the plunger. To meet these requirements, I provide a cap-holder D (Figs. 3, 6, 7 and 8) yieldingly carried concentrically by the plunger 21, and comprising a horizontal bottom plate, providing a floor, 41, carried by suspenders 42, carried by a top plate 43, provided with a hub 43^a through which passes slidably the plunger 21. The plate and its hub contain a counterbore 43^b (Fig. 3) disposed partly within which, and bearing against a washer 21^b carried by the plunger, is a spiral cushioning spring 44 encircling the therein portion of the plunger and by means of which it is enabled to yieldingly lift the cap-holder until the latter's ascent is, as indicated in Figs. 1 and 3, stopped by its contact with a stationary check-rod C^c carried, vertically adjustably, by the frame C. The cap-holder is, without unduly limiting its vertical movements relatively to the plunger, prevented from turning horizontally around the latter by means of a vertically extended recess, or slot, 21^c, into which enters vertically slidably the screw, or "feather", 43^c, carried by the hub 43^a. The cap-holder may also, preferably, comprise a thereby carried member 45, disposed above the extension 34^c of the chute, so as to intercept, deflect, and thus aid in guiding to required position, a cap which may, as sometimes happens, unduly bounce upward from the chute. To aid in securing, and in maintaining, correct alinement of the center of the cap with that of the opening in the can, and of the plunger during the latter's descent, I provide, movably supported upon the floor 41 and constituting an important feature of my cap-holder, a plurality of, in this instance four, horizontally, radially, resiliently, movable, alike, segmental members 46, 46', 46'', 46''', normally concentric with the central vertical axis of the plunger and normally mutually contacting. Each of said segments is, as shown in Fig. 5, concentrically, downwardly, beveled, as at 46^a toward their common central vertical axis, which is, normally, identical with that of the plunger and of the can during the pause in the advance of the latter when it is, as aforesaid, laterally supported, at the station B^a, by coaction of the guard rail A^{1a}, the flights A', and the rollers 27^c, 27^a, in the position indicated in Fig. 16. Each segment is radially slidably supported, on the floor 41, by means of a therein radially disposed slot, 46^b (Fig. 4) through which passes loosely a set-screw 41^a secured in the floor 41. The segments are, in this instance, yieldably forced toward, and held in, their

normal position, by means of the spiral contractile spring 47 disposed to surround, and bear equally against, the outward segmental periphery of each, and the tension of which is sufficient to resist their outward radial displacement by pressure from the plunger until after the cap-holder has contacted, and bears upon, a can.

To insure correct, horizontal, posing and presentation to the presser-foot, 21^a, of an irregularly, or, as shown in Fig. 3, obliquely delivered and deposited cap, I provide a yieldable follower, 48, in the form of a countersunk cylinder concentric with, resting normally on, supported by, and projecting slightly below, the presser-foot, as shown in Fig. 3. A spiral, easily-compressible, spring 49, encircling the shank 21^a of the presser-foot, bears against the follower and the plunger 21 thus delicately tempering the pressures imparted by the follower to such a misplaced cap in the path of its downward descent with the presser-foot.

The operation of my machine may be outlined as follows:—As a can is moved forward by the can-conveyer it encounters and bears against the roller 27^c thus actuating the trip-lever 27 and is then centered, and, during the pause of the can-conveyer, held stationary under the pressure-foot and cap-holder. While the centering is occurring the movement of the trip-lever has caused the separation of a cap from its associates in the chute, and its release, whereupon it slides by gravity into the bowl-like concavity presented thereto by the beveled inner edges of the segments of the cap-holder. The mechanisms are so timed that over the cap thus delivered the descent of the plunger begins; thus resulting, as is progresses, in firstly, administering to the cap the correctional yielding pressures imparted by the follower 48, and bringing it, if misplaced as in Fig. 3, to the correct position shown in Fig. 6. As the descent of the plunger continues, the floor of the cap-holder contacts, and is supported on, the top of the can, and the presser-foot enters the bowl of the cap as shown in Fig. 7. The continued descent of the plunger forces the cap downward, between the segments of the cap holder which radially make way for its thereby further guided passage therethrough, into the can-opening into which it is finally forced, into required position for crimping, by the conclusion of the plunger's downward stroke as shown in Fig. 8. This done, the advance of the can by the conveyer is resumed thus liberating the trip-lever with consequent return of the instrumentalities to normal position ready for the next can and cap as per the constructions heretofore described.

It will be noted that each of the operations of my above described devices are in-

dispensable to the cap-placing function of my machine as an organized entity, and are controlled by the advance to position of a can, without which they cannot normally operate. They are accurate and expeditious, are non-injurious to goods, cans, and caps, and they dispense entirely with the operator's handling of the latter at any stage.

Having now described my invention what I claim as new and desire to secure by Letters Patent is the following, viz;

1. In a machine for placing caps in cans means to move a can; means to support against gravity a plurality of mutually-contacting caps; means controlled by said can to separate a cap from said plurality; means controlled by said can to withdraw its said supporting means from said cap; means to guide toward said can the resulting descent of said cap; means controlled by said can to position said cap relatively thereto; and means controlled by said can to force said cap into required position in said can.

2. In a machine for placing caps in cans means to move a can; means controlled by a can to position a cap relatively thereto; and means controlled by said can to force said cap into required position in said can.

3. In a machine for placing caps in cans, a chute having a pathway for the caps in procession on an inclined floor between lateral guiding members and in said floor a transversely-extending opening; projecting into said pathway through said opening a stop carried by an underneath pivoted arm; an underneath movable plate comprising an angularly-extending opening within which said stop extends, and means to reciprocate said plate whereby said stop is moved in said openings into and out of said pathway.

4. In a machine for placing caps in cans, means to move a can, a chute having a pathway for the caps in procession on an inclined floor between lateral guiding members and in said floor a transversely-extending opening; projecting into said pathway through said opening a stop carried by an underneath pivoted arm; an underneath movable plate comprising an angularly-extending opening within which said stop extends, and means controlled by a can to reciprocate said plate whereby said stop is moved in said opening into and out of said pathway.

5. In a machine for placing caps in cans, a chute having a pathway for the caps in procession on an inclined floor between lateral guiding members and in said floor two transversely-extending openings; projecting into said pathway through each of said openings a pin each carried on an underneath pivoted arm; an underneath movable plate comprising two angularly-extending openings within one of which one of said

pins extends, and means to reciprocate said plate whereby one of said stops is moved into said pathway while the other is moved out, and vice versa.

6. In a machine for placing caps in cans means to move a can, a chute having a pathway for the caps in procession on an inclined floor between lateral guiding members and in said floor two transversely-extending openings, projecting into said pathway through each of said openings a pin each carried on an underneath pivoted arm, an underneath movable plate comprising two angularly-extending openings within one of which one of said pins extends, and means controlled by a can to reciprocate said plates whereby one of said stops is moved into said pathway while the other is moved out, and vice versa.

7. In a machine for placing caps in cans, means to move a can; a support for a can; above a can thereon supported a vertically movable plunger; and means controlled by said can to force downwardly said plunger.

8. In a machine for placing caps in cans, means to move a can; a support for a can; above a can thereon supported a cap-holder comprising a plurality of horizontally radially movable segments; above said holder a vertically movable plunger; and means controlled by said can to force downwardly said plunger between said segments toward said can.

9. In a machine for placing caps in cans, means to move a can; a support for a can; above a can thereon supported a cap-holder comprising a plurality of horizontally yielding segments; means to return them to normal position; normally above said holder a vertically movable plunger; and means controlled by said can to force downwardly said plunger.

10. In a machine for placing caps in cans, means to move a can; a vertically movable plunger; projecting normally below said plunger a therewith concentric vertically yielding follower; and means controlled by said can to force downwardly said plunger.

11. In a machine for placing caps in cans, a support for a can; above a can thereon supported a cap-holder comprising a plurality of horizontally yielding segments; normally above said holder a vertically movable plunger; projecting normally below said plunger a therewith concentric vertically yielding follower; means to force downwardly said plunger between said segments toward said can until said follower contacts a cap in said holder and thereafter until said plunger has forced said cap into said can; means to restore said plunger and follower to normal position; and means to restore said segments to their normal position.

12. In a machine for placing caps in cans, a support for a can; above a can thereon supported a cap-holder comprising a plurality of horizontally yielding segments; normally above said holder a vertically movable plunger; projecting normally below said plunger a therewith concentric vertically-yielding follower; means controlled by said can to force downwardly said plunger 5 between said segments toward said can until said follower contacts a cap in said holder and further until said plunger has forced said cap into said can; means to restore said plunger and follower to normal position; 10 and means to restore said segments to their normal position.
13. In a machine for placing caps in cans, means to move a can, a support for a can; above a can thereon supported a cap-holder 20 comprising a plurality of horizontally yielding segments; adjacent said holder means to support against gravity a plurality of mutually-contacting caps; means controlled by said can to separate a cap from said plurality means controlled by said can to withdraw its said supporting means from said cap; means to guide the resulting descent of said cap into said holder; normally above said holder a vertically movable plunger; 25 and means controlled by said can to force
- downwardly said plunger against said cap until it is forced into said can.
14. In a machine for placing caps in cans, means to move a can; a support for a can; above a can thereon supported a cap-holder 35 comprising a plurality of horizontally yielding segments; adjacent said holder means to support against gravity a plurality of mutually-contacting caps; means controlled by said can to separate a cap from said plurality; means controlled by said can to withdraw its said supporting means from said cap; means to guide the resulting descent of said cap into said holder; normally above said holder a vertically movable plunger; 40 projecting normally below said plunger a therewith concentric vertically-yielding follower; means controlled by said can to force downwardly said plunger between said segments toward said can until said follower 50 contacts said cap in said holder and further until said plunger has forced said cap into said can; means to restore said plunger and follower to normal position; and means to restore said segments to their normal position. 55
